ARMATURE PEGGING MACHINE

Hugh Valentine Williams, Richmond, Va.

Application November 14, 1947, Serial No. 786,077

2 Claims. (Cl. 29—205)

1

My invention relates to a method of and means for securing the coils in armatures; and particularly to the "pegging" of the coils in the armature slots; the object being to seal the coils in the slots. The process of sealing—or as it is commonly known: of pegging—consists of driving a strand of small rope or cord, or of twisted fabric, or even a strip of wood or of fiber, into the slot upon the top of the coil that has been placed therein. This process has been largely done by hand; a slow and an irregular operation. To preserve rotative balance of the armature it is important that the wires be laid compactly, and that they be securely held in place. This condition I attain by the use of my pegging machine, to be described herein.

Operation of the machine

The operation of my machine is, broadly, as follows: The armature is held in position opposite the end of a bed-plate; a driver-plate is arranged to slide forth and back upon or above the bed-plate; a length of pegging material is pushed onto the bed-plate near and parallel to the side of the armature and opposite to a slot in the side of the said armature. The length of pegging material is normally greater in diameter than the width of the armature slot. A plate above the pegging material descends, and squeezes it to a thickness which can be driven into the slot of the armature; and instantly the driver-plate makes a rapid forward stroke and drives the pegging material into the armature slot. At the same time, a knife attached to the descending squeezing plate cuts off that part of the pegging material which lies on the bed-plate from the main supply. If desired: already cut lengths of pegging material may be placed by hand upon the bed-plate. The driver-plate is then withdrawn; the squeezer plate (referred to hereinafter as the rocker plate) rises; and another length of pegging material is fed on to the bed-plate. The machine then comes to rest; and the armature is rotated to bring the next slot into position for pegging.

In the drawings: Figure 1 shows the machine in plan, at the end of a cycle; Figure 2, in plan, the machine with the driver-plate at the end of its forward stroke; Figure 3 is a diagrammatic view, in elevation, of the machine as shown in Figure 1; Figure 4 is a diagrammatic view of the machine as shown in Figure 2, but in elevation; Figure 5 is a partial elevation, showing a detail of the machine.

At one end of the base 2 there is supported a pneumatic cylinder 4, which is to be supplied with

air through the pipe 6, the air flow being controlled by the hand valve 8. This is a two-way valve so constructed that when the handle is depressed more or less air is admitted to the cylinder 4; and so that when the handle is released, the compressed air is cut off, and the air in the cylinder is exhausted to the atmosphere. The air admitted to the cylinder acts upon piston 10 (Figs. 3 and 4), to which is secured a piston-rod 12. The outer end 14 of the piston-rod is axially bored and tapped for a screw thread 16 upon the rod 18. The rod 18 is not screwed into the piston-rod end 14, as the rod 18 is not rotatable. But the piston-rod and the piston with it are turned so that the piston-rod thread 16 is turned upon the thread of the rod 18; the object being to provide means for adjustment of the stroke of parts of the machine. A wrench-flat 20 is provided on the piston-rod 12 to aid in the turning of the piston and the piston-rod.

At the farther end of the rod 18 is fixed a plate 22, which I term the driver-plate; and on this driver-plate is constructed an inclined plane or cam 24. This cam 24 may be conveniently made an extension of the rod 18; or it may be welded to the end of the said rod. It is also secured by welding or by other means to the upper surface of driver-plate 22; and so that its cam face is uppermost, and the lowest part 26 of the cam to the front. The weight of the end of the driver-plate, of the cam 24, and of certain attachments to the rod 18 (to be described later) is supported by the carriage 28, on which are mounted rollers 30, which roll upon the base 2.

When air is admitted to cylinder 4 the piston-rod 12, rod 18, cam 24, and driver-plate 22 move forward toward the armature 32, which is to be pegged. The armature is placed against a bracket 34, the height of which may be changed to hold armatures of different diameters, by placing suitable liners under the bracket, and adjusting the distance of the bracket from the bed-plate 36. This bed-plate 36 is set upon base 2; the elevation of this bed-plate being slightly less than that of the axis of the armature 32, so that the driver-plate 22 which slides upon the surface of the bed-plate 36 shall be directly opposite the axis of the armature; and so opposite to the nearest horizontally disposed armature slot 38 (Figs. 3 and 4).

We can now see that upon air being admitted to cylinder 4, the driver-plate 22 will be driven forward, toward the armature 32; and that by means of the adjustment provided by turning the piston-rod 12 upon the threaded rod 18 the approach of

the forward edge 40 of the driver-plate 22 to and into the armature slot 38 may be nicely regulated.

The driver plate 22 is retracted, when the air pressure on the piston 10 is released, by the simple means of the coiled springs 42, attached to brackets 44 on the rear cylinder head, and to a yoke 46, which yoke is mounted upon the threaded rod 18, and preferably held there by lock-nuts 48. The back stroke induced by springs 42 is limited by the stops or buffers 49, against which the yoke 46 strikes. The back stroke of the piston may be cushioned by air or by rubber or by other known means. The springs 42 are not shown in Figs. 3 and 4.

Feeding the pegging material

Adjacent the forward end of the bed-plate 36, and at its side, is the tube 50, through which the pegging material 52 is fed. This tube is mounted on suitable brackets attached to the bracket 54. Pivoted at 56 on a bracket 58 is the feeder-arm 60. Also pivoted, at 62, on bracket 58 is the bell-crank 64, the side arm 66 of which extends under cam 24 and rod 18, and behind the roller-carriage 28. The other end of the bell-crank 64 is connected by link 68 to feeder-arm 60. On the back stroke of piston 10 (induced by the springs 42) the roller carriage 28 strikes the end of bell-crank side-arm 66; throws the bell-crank 64; and, through link 68, the feeder-arm 60 is thrown to the position shown in Figure 1. On the forward stroke of the piston 10, the roller carriage 28 leaves the end of bell-crank side-arm 66; and the spring 70 pulls the feeder-arm 60 back to the position shown in Figure 2.

At the forward end of the feeder-arm 60 is pivoted, at 72, the finger 74; the pointed end 76 of which enters a slot 78 in the side of the tube 50. The spring 80 causes the pointed end 76 of finger 74 to bear upon the pegging material, shown here in the form of a cord, 52, within the slotted tube 50. The limit of the forward motion of finger 74 is governed by the relative movements of carriage 28 and of bell-crank side-arm 66; and it may be regulated by changing the leverage of link 68 on arm 60.

The limit of the backward movement of the feeder-arm 60 is governed by the position of the stop 82, which is pivoted at 84 on bracket 54. Its angular relation to the center line of the machine, and consequently the position of the stop 82, is set by means of the bolt 86 in the slotted arm 88 pivoted at 90.

At 92 is a spring finger, the free end of which presses lightly on the cord 52 in the tube 50, to prevent any retrograde movement of the cord therein. On each backward stroke of piston 10 and driver-plate 22 a measured length of cord will be fed across the bed-plate 36.

On each side of the bed-plate 36, and forming guides for the driver-plate 22, are brackets 94. On these brackets, at 96, is pivoted the rocker-plate 98. The forward end of this rocker-plate coincides substantially with the forward end of the bed-plate 36; while its rearward end is above the rear end of bracket 94, and also of bed-plate 36. At the rear end of rocker-plate 98 there is securely mounted a forked bracket 100, between the forks of which is mounted a roller 102. The pin 104 on which roller 102 rotates is carried in vertical slots 106 in the rearward end of the bracket; and in which slots the upward movement of the pin 104 is adjusted by the set-screws 108. The roller 102 "rides" on the surface of the driver-plate 22 (Fig. 3). In Figure 3 the piston 10, driver-plate 22, and cam 24 are shown re-

tracted. On the forward stroke of the same the cam 24 passes under roller 102, and so tips up the rear end and tips down the forward end of the rocker-plate 98 (Fig. 4). The space left between the forward end of the rocker-plate 98 and of the bed-plate 36, after the downward movement of the former, is regulated by the vertical adjustment of roller 102. After the retraction of the cam 24, the forward end of the rocker-plate 98 is caused to rise again, either by weighting the rear end of the said plate, or by spring action easily applied on the rear end of the plate or at the pivot 96. When the forward end of the rocker-plate 98 is raised, the measured length of pegging material is fed onto the bed-plate and under the end of plate 98. Then, on the admission of air to cylinder 4, the piston 10, piston-rod 12, cam 24, and driver-plate 22 will make a quick forward stroke. The forward end of the rocker-plate 98 will descend upon pegging material 52; press it to a thickness which can be pushed into the slot of the armature 32; and immediately thereafter the driver-plate 22 pushes the pegging material against the knife 112, severs the length desired, and drives it into the slot 38 of armature 32. The intensity and speed of the stroke of the driver-plate is regulated and controlled by the control of the air admission valve 8. Indeed: the stroke is so well controlled that the edge of the driver-plate may be gently used to press the pegging material into place; or by short strokes to hammer it into the slot and to a solid seat within the slot and upon the coils. The pegging material 52 is cut to length by means of a small knife 112 attached to the forward corner of the rocker-plate 98 on the side on which the material is fed. Its cutting edge 110, which is preferably ground at an angle to the horizontal plane, is turned to the rear, so that it may partially cut the pegging material on the downward stroke of the end of the rocker-plate 98, and also so that it may cut the material when the said material is driven against it by the forward stroke of the driver-plate 22. A detail of this knife is shown in Figure 5.

The pegging material may be of suitable kind and shape; but it is usually supplied in the form of either round or rectangular section.

The position of the armature adjacent the bed-plate is such that the driver-plate is opposite to the slot of the armature to be pegged. This position may be secured by placing upon the armature bracket or upon the end of the bed-plate or adjacent the bed-plate a tit over which the end of an armature slot may be slipped. When placed on or adjacent the bed-plate it is placed on a level with the driver-plate.

I claim:

1. In an armature pegging machine: in combination, a rectangular bed plate; reciprocating power means at one end of the bed plate set to reciprocate in the direction of the center line of and substantially parallel with the bed plate; adjacent the opposite end of the bed plate a bracket adapted to support an armature with a slot level with and in line with the end of the bed plate; a rocker plate pivotally mounted intermediate its ends on the bed plate and having its forward end over and in line with the forward end of the bed plate and parallel with the axis of the armature; a cam advanced by the reciprocating power means and adapted to engage and to raise the rear end of the rocker plate and so depress the forward end of the said rocker plate; means for depressing the rear end of the rocker

plate and so raising the forward end of the said plate on the withdrawal from the said rocker plate of the said cam; means for feeding pegging material onto the forward end of the bed plate, the said means being actuated by the reciprocating means toward the end of its backward stroke; a knife on the forward end of the rocker plate at the side adjacent the feeding means and with its cutting edge presented rearwardly and to the pegging material fed upon the bed plate; and a driver plate reciprocated between the bed plate and the rocker plate by the reciprocating power means to drive the pegging material against the knife to sever the length upon the bed plate and drive it into the armature slot.

2. In an armature pegging machine: in combination, a bed plate; reciprocating fluid pressure means located adjacent the bed plate and set to reciprocate in the direction of the center line of the bed plate; a rocker plate pivotally mounted on the bed plate to rock in the direction of the said center line, and having its forward end over and in line with the forward end of the bed plate; an armature supporting bracket adjacent the forward end of the bed plate and adapted to support an armature with its slots in line with and parallel to the end of the bed plate; a driver plate connected with and driven by the fluid pressure reciprocating means to reciprocate between the rocker plate and the bed plate; a cam mounted on the rear end of the rocker plate and adapted to engage on the for-

ward stroke of the reciprocating means the rear end of the rocker plate to raise it and to depress the forward end of the said rocker plate; a means for feeding pegging material onto the bed plate during the last part of the rearward stroke of the reciprocating means; means attached to the forward end of the rocker plate to sever a length of material from the supply; and fluid means hand-valve controlled and adapted to actuate the reciprocating means to drive the severed length of pegging material forward into a slot of the armature and on the latter part of the backward stroke to actuate the feeding mechanism; and also adapted by the control of the hand-valve to make half strokes of the driver plate to compact the pegging material and coils in the said slot.

HUGH VALENTINE WILLIAMS.
